UNITED STATES PATENT OFFICE

CHARLES MARKEL, OF SCHENECTADY, NEW YORK, ASSIGNOR TO BARCO MANUFACTURING COMPANY, OF CHICAGO, ILLINOIS, A CORPORATION OF ILLINOIS

CROSSHEAD AND SHOE

Application filed December 30, 1922. Serial No. 609,963.

This invention relates in general to cross-heads, and more particularly cross-heads having separable wear plates, or shoes as they are commonly termed, and has especial reference to the provision of an improved arrangement for detachable securing the shoes to a cross-head.

While this invention is illustrated as an improved means for detachably securing the shoes to a cross-head, the invention also embodies herewith certain improvements in the cross-head structure itself, and while reference is made to the use of the cross-head on a locomotive it will be readily apparent that it is applicable to any machine involving a similar function.

In a locomotive the cross-head reciprocates between guides located immediately to the rear of the cylinders, and forms the pivotal connection between the piston rod and the adjacent end of the pitman or crank. The chief function of the cross-head is to relieve the piston and piston rod of angular stress from the pitman. The slippers being subject to a greater amount of wear, tear and strain than the cross-head proper, it is often desirable to make them detachable to permit of replacement.

The cross-head as a whole is subject to vibration and shocks, and unless special provision is made for securing the slippers to the cross-head, the slippers will work loose not only from wear of the parts and connections but from the vibration.

It is advisable to make provision to prevent this tendency, and in addition, the arrangement and construction for supporting the slippers from the cross-head proper should be such as not only to give their connection the greatest security, but should also be of such a character as will permit of the ready detachability of the slippers from the cross-head, without disconnection or otherwise disassociating the cross-head, piston rod, or connecting rod.

The present invention is designed as a further adaptation of the features of the invention described and claimed in my co-pending application, Serial No. 497,784, and one of the principal objects of the present invention is

to generally improve and lighten the construction of the cross-head and shoe, more especially to the end that the construction thereof may be simplified and in order to facilitate repairs or replacements of parts while the cross-head is in service. 55

Among the principal objects of this invention, therefore, are: the provision of an arrangement for supporting and carrying the shoes from the cross-head proper which will keep them in rigid engagement and which will at the same time permit of the quick and easy dis-assembling of the cross-head and the replacement of the parts thereof, particularly the shoes; the provision of means for taking up any looseness which may develop between the shoes or slippers and the cross-head, and to bring the two into rigid contact should they work loose either through wear or for any other reason; the provision of a structure of the character referred to wherein I am enabled to so construct and connect the slippers to the cross-head as to provide the greatest structural strength at the points of greatest stress, to distribute the stress and in other ways provide an improved construction; the provision of an improved cross-head structure and removable slipper so related that the slipper may be conveniently detached or adjusted while the cross-head is in service and regardless of the position of the pitman; together with such further objects as will appear from the description hereto appended. 70 75 80

In the drawings:

Figure 1 is a fragmentary side elevational view of the device of this invention; 85

Figure 2 is a fragmentary end elevational view; and

Figure 3 is a plan view of the detachable shoe. 90

Referring more particularly to the drawing, 10 indicates a cross-head body, said body having a socket member 11 at one end thereof, said socket being provided with a reinforcing flange 12, and keyed or otherwise fixedly connected at 13 to one end of a piston-rod, not shown. To the rear of the socket 11, the cross-head is provided with a transverse enlarged aperture 14, said aperture serving to receive and retain a transverse pin (not 95 100

shown) to which is pivotally or otherwise connected a pitman or so-called connecting rod which transmits motion from the cross-head.

From an inspection of Figure 2 it will be observed that the cross-head body is somewhat barrel shaped, and that the body, adjacent the aperture 14, is reinforced by a flange 15, integral side walls 16—16 and 17—17 extending from said barrel and forming there-with a generally tapering structure as seen in Figure 1. The outer edges 16^a and 17^a of the walls 16 and 17 are inclined toward the forward end of the cross-head, that is, that end to which the piston-rod is connected.

The cross-head walls 16 and 17 and the shoes carried thereby being identical in most respects; I will therefore describe but one of the same.

It will be observed that the shoes, designated 18—18, are provided with channel portions 19, these channel portions being presented outwardly and receiving each one of the cross-head guides, not shown.

As previously pointed out, it is desired to adjustably yet firmly secure the shoe or slipper in its proper position on the cross-head, and to this end the shoe is provided, on its inner face, with a pair of integrally formed spaced longitudinal flanges 20 and 21, the outer or relatively remote surfaces 22 and 23 of said flanges being inclined, and adapted to engage complementally inclined inner surfaces 24 and 25, respectively, of the walls 16 and 17. The shoe is provided with the inclined surfaces 26 and 27 which engage the complemental surfaces 16^a and 17^a of the walls 16 and 17, and thus, with the engagement of the flanges 20 and 21 with the adjacent surfaces of the walls 16 and 17, a dovetailed connection is afforded between the shoe and cross-head and generally inclined with respect to the longitudinal axis of the cross-head. When the shoes are moved longitudinally relatively the cross-head it follows that such shoes will approach or recede from the longitudinal axis of the device. For a portion of the length of the shoe it is provided with recesses 28—28 which tend to lighten same.

It is necessary that some means be provided for adjusting the shoe relative to the cross-head, and to this end the shoe is provided, as best seen in Figures 1 and 3, with a transverse abutment 29, said abutment being arranged at the forward end of the cross-head, and formed integrally with said flanges 20 and 21. As will be seen in Figure 1 the outer and inner surfaces 30 and 31 of the abutment are inclined with respect to the longitudinal axis to a degree which places them substantially at ninety degrees to the plane of the inclined surfaces 16^a, and said abutment has a central opening 32 having its axis parallel with said surfaces.

The barrel body 10 of the cross-head is provided with spaced radial lugs 33 arranged to lie between the flanges 20 and 21, said lugs being disposed so as to receive between them a stud or bolt 34, the hexagonal head 35 thereof engaging behind said lugs in a suitable recess, and the threaded portion 36 extending through said opening 32, to receive a retaining and adjusting nut 37. The lugs 33 are arranged in the same plane parallel to the surfaces 30 and 31, and the recess behind said lugs prevents turning of the bolt 34.

It will be observed that the bolt 34, being parallel to the inclined surfaces of the shoe and cross-head, insures a direct motion of displacement of the shoe on the cross-head, and therefore, the bolt cannot bind. The angularity of the abutment 29 and the lugs 33 is such that the strain imposed thereon and upon the stud is distributed, which furthermore aids in preventing undue lateral stress on the parts.

In order to further insure the rigid securing of the shoe on the cross-head, after an adjustment, the flanges 20 and 21 are provided with a series of elongated slots 38, these slots being arranged complementally in pairs, one in each flange, and adapted to receive the shanks of transverse bolts 39—39, which bolts pass through aligned apertures in the walls 16 and 17. Nuts 40 secure said bolts against displacement. Expanding lock-washers 41—41 are provided on the bolts 34 and 39 for an obvious purpose.

When this invention is installed on a locomotive or any other reciprocating steam engine, the barrel 11 is keyed to the piston rod and the pitman or connecting rod (not shown) is pivotally connected at the rear end of the cross-head in said opening 14. The cross-head as shown is arranged for installation on a locomotive having two parallel guides, that is, one guide above and one below the cross-head for surface engagement with one each of said shoes 18. After the cross-head has been placed in position with the shoes attached thereto, the bolts 39 may be loosened and the nuts 37 tightened so that the shoes are caused to slide rearwardly and move outwardly relative the cross-head into proper surface engagement with the guide, whereupon the lock washers 41 are placed on the bolts 34. The bolts 39 are then tightened by turning up the nuts 40 and the lock washers for said nuts are applied.

It will be observed that the shoes may be individually adjusted relatively to the cross-heads, and that these shoes may be readily removed as required regardless of the position of the pitman. This is rendered possible by virtue of the fact that the shoes may be removed only in the direction toward the piston rod (not shown), when the device is in operative position. Thus, if one of the shoes is fractured or otherwise damaged or

worn out in service the shoe may be readily replaced without the necessity of disconnecting the cross-head from the piston rod or from the pitman or connecting rod. The skeleton construction of the cross-head and shoes tends to lighten the device without sacrificing strength and rigidity. Furthermore, any tendency of the shoes and cross-head to vibrate or move relatively in service is effectually prevented by the provision of the dove-tailed connection and its cooperation with the bolts 34 and 39.

Having thus described my invention and illustrated its use, what I claim as new and

15 desire to secure by Letters Patent is:—

1. In a device of the character described, in combination, a cross-head having inclined surfaces, wearing plates provided with inclined surfaces engaging the inclined surfaces of the cross-head and extending beyond the ends of said cross-head, said cross-head being provided with lugs, complementary lugs on said wearing plates, and means parallel with said inclined surfaces passing through 25 the lugs adapted to exert a self-centering force on said cross-head and plates for adjusting and securing said plates.

2. In a device of the character described, in combination, a cross-head having inclined surfaces, wearing plates provided with inclined surfaces engaging the inclined surfaces of the cross-head and extending beyond the ends of said cross-head, said cross-head being provided with lugs, complementary 35 lugs on said wearing plates, and means parallel with said inclined surfaces passing through the lugs adapted to exert a self-centering force on said cross-head and plates for adjusting and securing said plates.

40 3. The combination with a cross-head having means for connecting a piston rod to one end thereof, of a slipper on said cross-head, said slipper and cross-head being reversely tapered to compensate for wear of the slipper, one end of said cross-head carrying said 45 piston rod connection, and means arranged in a plane parallel to the taper of said cross-head adjacent the said piston rod for exerting pulling force on the slipper longitudinally of the cross-head and for securing said 50 slipper to said cross-head.

4. The combination with a cross-head having means for connecting a piston rod to one end thereof, of a slipper on said cross-head, said cross-head having spaced walls provided with inner inclined dove-tail surfaces, said slipper having spaced longitudinal flanges complementary to said spaced walls and receivable between the same, and having outer 55 inclined dovetail surfaces, the flanges and walls of said slipper and cross-head being reversely tapered to compensate for wear of the slipper, spaced lugs on the cross-head extending into the space between said flanges, 60 a bolt having a nut and extending through a

part of said slipper and along the central longitudinal axis thereof parallel to the tapered line of the slipper and cross-head and engaging said lugs, whereby upon tightening said nut said slipper is drawn along the 70 cross-head and self-centered thereon.

In testimony whereof I have hereunto signed my name.

CHARLES MARKEL.
